BOW MAKING MACHINE

Gershom N. Carmichael, 6315 Robinhood Lane,
Merriam, Kans.

Filed Apr. 19, 1963, Ser. No. 74,521

Term of patent 3½ years

(Cl. D55—1)

Fig. 1.

Fig. 2.

Fig. 3.

Fig. 4.

FIG. 1 is a side elevational view of a bow making machine, showing my new design;

FIG. 2 is a top plan view thereof;

FIG. 3 is an elevational view showing one end; and

FIG. 4 is an elevational view showing the opposite end of bow making machine.

I claim:

The ornamental design for a bow making machine, as shown.
